(57) **CLAIM**

The ornamental design for a syringe for dental use, as shown and described.

DESCRIPTION

FIG. 1 is a front elevational view of a syringe for dental use, the rear elevational view being a mirror image of the front elevational view;

FIG. 2 is a top plan view thereof;

FIG. 3 is a bottom plan view thereof;

FIG. 4 is an enlarged left side elevational view thereof;

FIG. 5 is an enlarged right side elevational view thereof;

FIG. 6 is a cross-sectional view along line 6-6 in FIG. 4; FIG. 7 is a front elevational view thereof prior to use, the rear elevational view prior to use being a mirror image of the front elevational view prior to use;

FIG. 8 is a top plan view thereof prior to use;

FIG. 9 is a bottom plan view thereof prior to use;

FIG. 10 is an enlarged left side elevational view thereof prior to use;

FIG. 11 is a cross-sectional view along line 11-11 in FIG. 10; FIG. 12 is a front elevational view thereof after use, the rear elevational view after use being a mirror image of the front elevational view after use;

FIG. 13 is a top plan view thereof after use;

FIG. 14 is a bottom plan view thereof after use;

FIG. 15 is an enlarged left side elevational view thereof after use;

FIG. 16 is a cross-sectional view along line 16-16 in FIG. 15;

FIG. 17 is a front elevational view of a plunger thereof;

FIG. 18 is a top plan view of the plunger thereof;

FIG. 19 is a cross-sectional view along line 19-19 in FIG. 17; and,

FIG. 20 is a view of the section at line 19-19 in FIG. 17.
